UNITED STATES PATENT OFFICE

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY

HEEL-ATTACHING MACHINE

Application filed September 5, 1923. Serial No. 661,072.

This invention relates to heel-attaching machines, and more especially to that constituent mechanism which presents heels or heel-portions, as the bases and top-lifts, to the nailing mechanism.

Such heel-holders have members, for example the holding device or swing-plate as a whole, or the spanker-plate associated with the top-lift-holder, which it may be desired 10 to vary in position when the size of the work-portion changes, and in some cases, as in the shifting from a heel for a man's shoe to that for a woman's shoe, the extent of movement may be considerable. It has been customary 15 to effect the adjustment by means of a screw-connection to the member to be moved, but where the range is great, this is slow and troublesome. As a feature of the invention, I facilitate the change by the provision of 20 means for producing both a rapid and gradual adjustment, the former giving an approximate setting of the member, and the latter a more exact positioning, or serving alone when the alteration to be made is slight. 25 Another feature of the invention involves so positioning the various parts of a holder for heel-portions with reference to each other and to the shoe to which the portions are to be attached that such portions are effectively grasped and accurately presented. 30 There may be provided adjustments of the holding mechanism or swing-plate as a whole, of the clamping members or jaws, and of the gage or back-stop which co-operates with 35 said clamping members.

A further feature concerns a connection between the clamping members or jaws which will insure their free movement. This connection, which includes a spring acting to 40 force the clamping members toward each other, has a movement of self-adjustment along the jaws while engagement with opposite edges thereof is maintained. It preferably comprises a retaining member or casing movable upon the jaws, and a spring carried by the casing and contacting with said jaws. There may be means associated with the casing to vary the normal separation of the jaws.

When oscillatory clamping jaws are con-

nected to move together, as by intermeshing teeth, these teeth may wear, so they do not properly engage. As still another feature of the invention, I compensate for this wear by a variation in the relation between the mountings of the jaws, as by pivoting them upon studs which have eccentric portions. 55

Such an adjustment as that of the jaw-pivots just mentioned, when made in connection with a bodily movement of the jaws upon a pivoted carrier through a definite angle, tends to disturb the extent of angular movement, and, to maintain the correct angular relation, I provide, as a feature of the invention, for adjustment of the movement of the carrier, the adjusting means being preferably 60 readily accessible. As illustrated, this adjustment is effected by screws threaded through a member upon the upper extremity 65 of the spindle, by which the carrier is pivoted. 70

An additional feature of the invention has to do with the control by the holding mechanism of the nail-transferring or loading mechanism. To prevent the delivery of nails by the loading mechanism when a top-lift is 75 being presented by the holding mechanism, the latter mechanism actuates a locking member for the former. This operation, with an oscillatory holder of the character herein described, I prefer to accomplish by means of a 80 yieldable arm, oscillating with the holder and its spanker-plate and engaging a latch, to move it to holder-locking position.

The accompanying drawings illustrate a particular embodiment of my invention, 85

Fig. 1 being a perspective view of a heel- 85 ing machine to which my improvements are applied;

Fig. 2, a vertical section on the line 2—2 of Fig. 3 and including a portion of the jack; 90

Fig. 3, a top plan view of the holding mechanism, with parts broken away;

Fig. 4, a perspective view of said mechanism, with portions removed;

Fig. 5, a vertical section on the line 5—5 of Fig. 3;

Fig. 6, a vertical sectional detail on the line 6—6 of Fig. 1;

Fig. 7, a similar view on the line 7—7 of Fig. 3;

Fig. 8, a perspective view of separated elements of the latching device for the safety-bar; and

Fig. 9, a vertical sectional detail on the lines 9—9 of Fig. 4.

At 10 appears a portion of the frame of a heel-attaching machine of the type disclosed in the patent in my name numbered 446,885 and dated Feb. 24, 1891. This frame supports the holder 12 for a die-block 14, and in it reciprocates the side rods 16, 16 connected by a top girt 18, upon which are carried drivers 20, said die-block and drivers co-operating to furnish the nail-driving mechanism. Nails may be delivered to the die-block-openings by a loader-block 22 carried by the extremity of a loader-arm 24 arranged to swing about one of the side rods 16. The movement of this loader-block is between a receiving position, as appears in Fig. 1 of the drawings, in which its openings are supplied with nails, and a nail-delivering position over the die-block, in which said nails are deposited in the die-block-openings.

Secured at the back of the die-block-holder is a supporting bar or elongated bracket 26, having near its center a horizontal rearward extension 28, passing vertically through which is a longitudinal slot 30. In this bracket-extension, beneath the slot, are ways 32 to receive a slide 34, from which rises a tubular post 36 movable along the slot 30. Rotatable in the post is a spindle 38 having fixed at its lower extremity a swing-plate 40 or carrier 40 for a heel-holding device A and a top-lift-holding device B. The swing-plate is rotatable by means of a handle 42 depending from it, to bring either the heel-holder or the top-lift-holder into a position in which the heel-portion carried is presented beneath the die-block for the nailing operation, it being at the same time positioned above the heel-seat of a shoe S supported upon a jack 44. The axes of the holding devices A and B are separated by 90 degrees, and the angular movements of the swing-plate to its opposite extremes, in which the respective heel-portions are brought into the attaching position, are determined by screws 46, 46 threaded through a block 48 keyed near the upper extremity of the spindle 38. A nut 50 upon the threaded upper extremity of the spindle holds the block against upward movement, and by the contact of the latter with the top of the post 36, prevents the downward displacement of the swing-plate. The ends of the screws 46 contact with opposite surfaces upon walls 52, 52 rising from the bracket 26 at each side of the slot 30. The swing-plate is spaced from the bottom of the bracket 26, and within this space are clamping jaws 54, 54 pivoted at 56, 56 upon the upper face of the swing-plate. The outer extremities of the jaws have roughened surfaces 58 adapted to grasp the periphery of a heel near the breast. The jaws are connected to move together simultaneously in opposite directions by intermeshing portions or teeth 60, 60. The engaging surfaces 58 are forced yieldably toward each other, to bring the jaws into such relation that they will grasp the smallest heel which is to be attached, by a spring 62, the ends of which contact with the opposite inner edges of the jaws near their inner extremities. This spring is contained in a tubular casing or retaining member 64 slotted at 66, 66 so the ends of the jaws may pass through the casing to receive the pressure of the spring. At the outer edges of the jaws, where the casing co-operates with them, are depressions 68, 68 retaining such casing against displacement to any great extent in either direction, yet permitting a free movement of self-adjustment longitudinally of the jaws. By this means, binding or cramping of the spring and its retaining member is prevented, this being especially useful when the oscillation of the jaws is considerable. One extremity of the casing is threaded to receive a nut 70. This, contacting with the inner wall of the depression 68 at this side, may be adjusted in either direction to vary the normal extent of separation between the heel-engaging surfaces 58. It serves to adapt the space between the jaws to the heel of minimum width which is to be operated upon.

The correct meshing of the projections 60 may be interfered with by their wear, and to take up the lost motion, the pivots 56 are shown as in the form of studs fixed on the swing-plate by nuts 72 (Fig. 9) threaded upon their lower ends. The heads 74 of the studs, about which the clamping jaws turn, are eccentric to the axes of the studs proper. Consequently, the studs may be turned and fixed by the nuts in different positions, thus varying the pivotal points of the jaws. Usually, this taking up of the backlash in the intermeshing projections is effected by the operator through a change in but one of the jaw-pivots. The effect of this is to alter the central axis of the pair of jaws, which would modify the angle through which the clamping devices turn in presenting alternately a heel and a top-lift. In such event, the desired 90 degrees of rotation may be restored by a change in the extent of projection of the stop-screws 46.

To change the relation of the heel H, grasped by the jaws 54, to the die-block-openings, thus providing for the most effective location of the nails in heels of one size or another or those differing in pitch, the slide 34, and thus the swing-plate as a whole, is adjusted. The illustrated means for the purpose consists of a screw 130 turning in a lug rising from the slide and having threaded engagement with the bracket-extension 28. Since the shift from the heels of men's to

those of women's shoes is of substantial extent, it is facilitated by a quick-and-slow adjustment, furnished by a partial nut 132 (Fig. 3) movable in a recess in the bracket-
5 extension and carried by a stem 134 and nor-
mally pressed into engagement with the
thread of the screw 130 by a spring 136. The
stem furnishes an actuating portion project-
ing from the nut-section through a lateral
10 bore in the extension 28, the spring lying
within this bore about the stem and being
interposed between the nut-section and a plate
138 closing the end of the bore. Upon the
extremity of the stem is a head 140 to be
15 grasped by the operator to withdraw the nut-
section from engagement with the screw when
the quick adjustment is desired.

Located between the jaws 54 is a back stop
or gage 76 for the heel H, fixed upon the
20 forward extremity of a plate 78 arranged to
slide in ways in the top of the swing-plate and
being slotted at 80 to permit the passage of
the spindle 38 and the sleeve in which it
rotates. At the opposite end of the plate 78
25 is a screw 82 arranged to rotate in a yoke 84
fixed to the swing-plate. The screw is
threaded into the plate 78, and when turned
moves said plate, and therefore the back stop
76, in one direction or the other, thus chang-
30 ing its relation to the ends 58 of the jaws.
This adjustment alters the points along the
curved periphery of the heel at which the
ends of the jaws engage it, so it may be most
firmly held against displacement under the
35 influence of its weight or of jaw-pressure.

Carried in ways 85 in the swing-plate, be-
low the jaws 54, is a slide 86, upon which are
mounted top-lift-holding jaws 88, 88. The
40 form of these jaws may be substantially
identical with that of the jaws 54, 54, so
that they may all be stamped out by a single
die. They are connected by teeth 90 corre-
sponding to the teeth 60 of the heel-holding
45 jaws, and are arranged to oscillate about ad-
justable pivots 92 similar to the pivots 56. A
pressure device 94 forces surfaces 96, 96 to-
ward each other for engagement with a top-
lift in the same manner as the heel-jaws.

Between the jaws 88, 88 is a back stop 98
50 carried by an arm 100, which first extends in
a generally horizontal direction below one of
the jaws, then turns and descends vertically
to the lower portion of the swing-plate, where
it again assumes a horizontal direction, being
55 connected to a slide 102 movable in ways 104.
A screw 106 turns in a bracket 108 depending
from the yoke 84, and is threaded through a
lug projecting from the slide 102. By the
60 rotation of this screw, the advance or with-
drawal of the back stop 98 between the jaws
88 may be effected, so that the correct posi-
tioning of the top-lift for heels of different
sizes and pitches may be accomplished. This,
65 it will be seen, is independent of the similar

effect obtained for the heels by movement of
the slide 34 with the jaws 54.

After the adjustment of the back stop in
accordance with the character of the top-lift
operated upon, it may be desired to vary the
70 relation of the clamping jaws to said back
stop. This permits the engaging portions
96 of the jaws to be brought into contact with
the periphery of the top-lift at a greater or
less distance from the breast, so the retention
75 of the object may be assured. Were the jaws
to engage the top-lift at points too far toward
the rear, it will be obvious that the curvature
of the periphery would tend to cause its
ejection by the pressure against it. This ad-
80 justment may be effected for the jaws 88 by
a movement of their supporting slide 86. To
this end, a screw 110 turns in a lug depending
85 from the slide, and is threaded into the lower
portion of the swing-plate. Rotation of this
screw, by its engagement with the lug causes
a movement of the slide 86 to change the
distance of the engaging extremities of the
jaws from the back stop.

Above the jaws 88 is located the usual
spanker-plate 112, this being forced against
90 a top-lift grasped between the jaws 88 to force
it upon the ends of the previously-driven
nails which have been left projecting from
an attached heel. To allow the forward edge
95 114 of the spanker-plate to be differently po-
sitioned longitudinally of the jaws, so that
it will serve with different sizes of top-lifts
as a gage by which the operator may deter-
mine the proper angular relation of the top-
lift between the jaws, it is fixed to a block
116 movable along a screw 118, the inner
100 end of which turns in the swing-plate. The
distance through which the spanker-plate
must be moved for this purpose may be con-
siderable, as when a change from the nailing
the heels of men's to those of women's shoes
105 is made. The use of a threaded adjustment
only in this connection would materially
delay the operator. I therefore provide both
110 a quick and a slow adjustment of the spanker-
plate. The screw 118 passes through an un-
threaded bore in the block 116, and at one
side of this bore, in a recess in the block, is
located a threaded section 120 furnishing a
115 partial nut. This section is fixed upon a
plate 122 movable in a depression at the
outer side of the block. The plate, above
the nut-section, has a horizontal stem 124
(Fig. 6) projecting into a bore in the block
120 and being provided at the opposite side of
said block with an enlargement or head 126.
Surrounding the stem between the inner end
of the bore and the head 126 is a spring 128,
which acts to hold the section 120 normally
125 in engagement with the thread of the screw
118. By pressing upon the head 126, the op-
erator may entirely free the screw 118 from
threaded engagement, so the spanker-plate
may be carried back and forth by direct
130

135

movement. This furnishes a very rapid adjustment when the difference in size between the parts to be held is considerable. Upon release of the head 126, the spring 128 carries the nut-section 120 into engagement with the thread of the screw. Then, by turning said screw, the spanker-plate may be moved more slowly and with greater precision. In this way, the spanker-plate may be finally accurately adjusted; or this rotary threaded adjustment may be utilized when the distance through which the spanker-plate is to be shifted is relatively slight.

A slot 142 in the loader-arm receives a pin 144 rising from the usual safety-bar 146 mounted to reciprocate upon the bracket 26. This safety-bar, by the engagement of the slot with the pin, is moved when the loader is carried over the die-block, to prevent movement of the starting lever of the machine, as is made clear in Patent No. 446,885, previously mentioned. This guards against actuation of the machine when the loader-block is in a position in which it would be struck by the descending drivers. By locking the safety-bar, the oscillation of the loader-arm may also be prevented, since the presence of the pin 144 in the slot 142 holds the loader-arm when the safety-bar cannot be reciprocated. Such a locking of the safety-bar I employ when the swing-plate is in top-lift-presenting position to avoid the possibility of a load of nails being deposited upon the top of the spanker-plate. To bring this about, there is arranged to slide upon one of the walls 52, at right angles to the safety-bar, a latch 148 (Figs. 1 and 8) having a locking projection 150 for engagement with a depression 152 in the rear side of the safety-bar. To maintain a normal withdrawal of the latch from the depression 152, a spring 154 (Fig. 7) is situated in a recess in the top of the wall 52 between the end of said recess and a depending portion 156 of the latch. Fixed upon the top of the spindle 38 is a spring-arm 158. The angle at which this arm projects from the spindle is such that as the top-lift-holding device B approaches the die-block, the end of this arm engages the rear portion of the latch, and forces it against the spring 154 into the safety-bar-depression 152. Therefore, before the spanker-plate arrives beneath the die-block-openings, the safety-bar is locked, and upon an attempt to move the loader-block over the die-block, the wall of the slot 142 contacts with the now locked pin 144, so that a delivery of nails upon the top of the spanker-plate is impossible. The yield of the arm 158 circumferentially of the spindle 38 allows for an excess of its movement over the travel of the latch 148.

Having described my invention, what I claim as new and desire to secure by Letters Patent of the United States is:—

65 1. In a holder for heel-portions, a mount-

ing arranged to permit the holder to move for the presentation of the heel-portions to operating mechanism, an adjustable member for engagement with a heel-portion, means arranged for actuation by the operator to impart to the member a gradual movement of adjustment, and means arranged to free the member from the moving means to permit it to receive a more rapid movement.

70

2. In a heel and top-lift-holder, a support, a slide movable upon the support, a swing-plate mounted upon the slide, heel-holding means carried by the swing-plate, top-lift-holding means carried by said swing-plate, a screw engaging the slide, and a threaded member mounted upon the support and movable into and out of engagement with the screw.

75

3. The combination with a top-lift-holder, of a movable spanker-plate, a movable block by which the plate is carried, a screw rotatable to move the block, and a threaded member mounted upon the block and movable into and out of engagement with the screw.

80

4. The combination with nailing mechanism, of a carrier co-operating therewith and movable in a plurality of directions, means arranged to adjust the position of the carrier with reference to the nailing mechanism by movement in one direction, opposite clamping members for heel-portions movable upon the carrier, means arranged to adjust the members upon the carrier, a gage member mounted upon the carrier and co-operating with the clamping members, and means arranged to adjust the gage member upon the carrier.

85

5. The combination with nailing mechanism, of a carrier movable into and out of co-operation with the nailing mechanism and in a direction transverse to such path of movement, means arranged to vary the position of the carrier in the transverse direction, opposite clamping members for heel-portions movable upon the carrier, means arranged to adjust the members upon the carrier, a gage member mounted upon the carrier and co-operating with the clamping members, and means acting independently of the clamping members and arranged to adjust the gage member upon the carrier.

90

6. The combination with nailing mechanism, of a swing-plate, means arranged to vary the position of the plate independently of its swinging movement, pairs of heel and top-lift-clamping jaws pivoted upon the swing-plate, means arranged to adjust bodily a pair of jaws upon the swing-plate, a back-stop movable upon the swing-plate between the jaws of each pair, and means arranged to adjust each back stop independently of the jaws.

95

7. In a heeling machine, a support, a slide movable thereon, a swing-plate pivoted upon the slide, a pair of clamping jaws pivoted

100

105

110

115

120

125

130

- upon the swing-plate, three slides movable upon the swing-plate, a pair of clamping jaws pivoted upon one of the slides, and a back stop mounted upon each of the other two slides and co-operating with the pairs of jaws.
5. 8. In a holder for heel-portions, clamping members movable toward and from each other to grasp and release a heel-portion, and a connecting device for the members arranged for movement of self-adjustment longitudinally of said members while engagement with opposite edges thereof is maintained.
10. 9. In a holder for heel-portions, a pair of work-engaging jaws constructed and arranged to present a heel-portion for an operation upon it, and a spring acting to force the jaws toward each other and arranged for movement longitudinally upon the jaws.
15. 10. In a holder for heel-portions, a pair of work-engaging jaws, a retaining member mounted to move upon and contacting with both the jaws, and a spring carried by the retaining member and contacting with the jaws.
20. 11. In a holder for heel-portions, a pair of work-engaging jaws, a retaining member mounted to move upon the jaws, a spring carried by the retaining member and contacting with the jaws, and means adjustable upon the retaining member and serving to vary the normal separation of the jaws.
25. 12. In a holder for heel-portions, a pair of work-engaging jaws, a casing movable upon the jaws, and a spring situated in the casing and contacting at its ends with the jaws.
30. 13. In a holder for heel-portions, a pair of work-engaging jaws, a casing having slots through which the jaws pass, and a spring situated in the casing and contacting at its extremities with the jaws.
35. 14. In a holder for heel-portions, a pair of work-engaging jaws, a threaded casing having slots through which the jaws pass, a spring situated in the casing and contacting at its extremities with the jaws, and a member engaging the casing-thread and against which one of the jaws is forced by the spring.
40. 15. In a holder for heel-portions, a pair of oscillatory work-engaging jaws having connections to cause them to move together, a pivotal mounting for each jaw, means arranged for manipulation by the operator to vary independently of the oscillation of the jaws the relation between the pivotal mountings, and means arranged to fix the mountings in their new relation.
45. 16. In a holder for heel-portions, a pair of oscillatory work-engaging jaws having intermeshing teeth, and rotatable studs having eccentric portions upon which the jaws are mounted.
50. 17. In a holder for heel-portions, a pivoted carrier, a pair of jaws pivoted upon the carrier and movable therewith into different work-presenting positions, means arranged to vary the pivotal points of the jaws, and means arranged to adjustably determine the movement of the carrier.
55. 18. In a holder for heel-portions, a support, a carrier pivoted upon the support, screws arranged to adjustably limit the movement of the carrier, oscillatory work-engaging jaws, and eccentric pivots adjustable upon the carrier and about which the jaws oscillate.
60. 19. In a heel-attaching machine, a die-block holder, a support secured thereto, a vertical spindle mounted to turn in the support, heel and top-lift-holders carried by the spindle, a member fixed to the upper extremity of the spindle, and screws threaded through the member and arranged to contact with walls of the support adjacent to the spindle.
65. 20. In a heel-attaching machine, nailing mechanism, nail-transferring mechanism delivering to the nailing mechanism, a member movable to lock the transferring mechanism against delivery, an oscillatory heel and top-lift-holder, said top-lift-holder being provided with a spanker-plate, and an arm oscillating with the holder and engaging the member to move it to locking position.
70. 21. In a heel-attaching machine, nailing mechanism, nail-transferring mechanism delivering to the nailing mechanism, a reciprocating latch for the transferring mechanism, an oscillatory spindle, a heel and top-lift-holder carried by the spindle, and an arm fixed to the spindle and constructed and arranged to contact with the latch and to yield circumferentially of said spindle.
75. 22. In a holder for heel-portions, a movable member for engagement with a heel-portion, a screw connected to the member, an element provided with an opening through which the screw extends and with a recess adjacent to the opening, a threaded member situated in the recess for engagement with the screw, and means carried by the member and extending therefrom outside the recess and arranged for manipulation by the operator to vary the relation of said member to the screw.
80. 23. In a heel and top-lift-holder, a support, a slide movable upon the support, a swing-plate mounted upon the slide and being provided with heel and top-lift clamps, a screw rotatable in the slide, there being a recess in the support adjacent to the screw, and a threaded member movable in the recess into and out of engagement with the screw.
85. 24. In a heel and top-lift-holder, a support, a slide movable upon the support, a swing-plate mounted upon the slide and being provided with heel and top-lift clamps, a screw rotatable in the slide, there being a recess in the support adjacent to the screw, and a threaded member movable in the recess and

provided with an actuating portion projecting outside the recess.

25. The combination with a swing-plate, of a top-lift-holder movable thereon, a movable spanker-plate, a movable block by which the plate is carried, said block being provided with a recess, a screw rotatable upon the swing-plate adjacent to the recess, and a threaded member movable in the recess into and out of engagement with the screw.

10 26. The combination with a swing-plate, of a top-lift-holder movable thereon, a movable spanker-plate, a movable block by which the plate is carried, said block being provided with a recess, a screw rotatable upon the swing-plate adjacent to the recess, a plate movable in the recess and having a threaded portion for engagement with the screw, and a stem projecting from said plate through the block at the opposite side of the recess.

15 27. In a holder for heel-portions, a movable member for engagement with a heel-portion, a screw connected to the member, an element provided with an opening through which the screw extends and with a recess adjacent to the opening, a threaded member situated in the recess, and a spring in the recess arranged to force the threaded member into engagement with the screw.

20 28. In testimony whereof I have signed my name to this specification.

JOSEPH H. POPE.
